UNITED STATES PATENT OFFICE

149,332

DESIGN FOR A KNIFE

Grosvenor N. Allen and William Gerth, Oneida,
N. Y., assignors to Oneida Ltd., Oneida, N. Y., a
corporation of New York

Application September 26, 1946, Serial No. 133,582

Term of patent 14 years

(Cl. D22—3)

To all whom it may concern:

Be it known that we, Grosvenor N. Allen and William Gerth, citizens of the United States, residing at Oneida, county of Madison, and State of New York, have invented a new, original, and ornamental Design for a Knife, of which the following is a specification, reference being had to the accompanying drawing, forming a part thereof, in which,

Figure 1 is a flat view of a knife showing our new design;

Figure 2 is a back view of the knife; and

Figures 3 and 4 are enlarged cross sections taken on the respective lines 3—3 and 4—4 of Figure 1.

The essential feature of our new design is the ornamentation on the handle of the knife.

We claim:

The ornamental design for a knife, substantially as shown and described.

GROSVENOR N. ALLEN.
WILLIAM GERTH.
